ARRANGEMENT FOR THE WET TREATMENT
OF SPINNING CAKES, ETC.

Ferdinand Rathgeber, Arnhem, Holland, Walter Schulz, Viktor Beplate, and Adolf Ruesch, Sydowsau, near Stettin, Germany, assignors to North American Rayon Corporation, New York, N. Y., a corporation of Delaware

Application January 12, 1931, Serial No. 508,364
In Germany January 11, 1930

20 Claims. (Cl. 18—8)

The process and arrangement in question refer to the wet treatment of spinning cakes, etc. in which the spinning cakes are hung upon washing sticks and pass through dripping baths. According to the process the carrying sticks, for the sake of brevity referred to as washing sticks, are arranged in several rows and are laid into the grooves which have been cut on both sides of the machine frame. These washing sticks are transported mechanically from groove to groove. This transportation of the washing sticks requires a comparatively short time and the washing sticks may thus be exposed somewhat longer to the drip washing. In order to obtain an intensive and thorough washing, the spinning cakes are turned or rotated mechanically on each row by turning the cakes for instance half a revolution so that the hanging end will lie on the stick on the next following groove. In order to improve this process still further the spinning cakes, which are to be subjected to the wet treatment, are wrapped in suitably meshed cloth covers in order to prevent any damage to the yarn when the cakes are turned. For instance, for this purpose, knitted viscose material in the form of hose may be used, in which the cake is wrapped and the two free ends of the hose may be slipped within the cake by which means the spinning cake is covered like a ring. According to this process the washing liquid is used in the same manner for several or all rows of the drip washing zone and is allowed to drip from row to row. Provision has also been made so that the liquids of each upper row are collected above each lower row and are distributed by means of a suitable distribution arrangement in the same way as on the upper row.

Besides the usual dripping grooves dripping boxes have proven especially satisfactory which may cover several washing sticks and which contain several rows of dripping holes which are located in depressions in the bottom of the boxes, and arranged in rows above the various washing sticks. According to the process different kinds of dripping or treating baths may be used in the various dripping areas which follow each other so that part or all of the wet treatment operation may be effected in proper sequence such as is required for the spinning cakes of certain kinds. Thus, the viscose rayon may be freed from salts and acids, desulphurized, bleached, subjected to various acidifying operations, thorough washing, avivage, oiling and even sizing in proper sequence.

The arrangement consists in an oblong fixed frame scaffold which has a channel-like space in the interior thereof. On both sides of the interior, lengthwise traverse ledges are fixed rigidly, according to the different rows, and have grooves for properly placing the washing sticks. Each row has movable carrying scaffolds hanging on carrying levers or indirectly on cranks in order that the carrying frame may be moved. The carrying frames also have grooved carrying ledges for the sticks and the grooves lie in their normal position besides the grooves of the fixed ledges. With the suitable groove intervals and crank lengths the sticks may be moved in regular intervals from one to the next following groove of the fixed frame when the crank system is in movement. The carrying frames of all the rows may be fixed to the same carrying levers and cranks, and all cranks or drive shafts may be moved by a common drive shaft situated lengthwise of the machine by means of helical gears, beveled gears, etc. In order to keep the weight of the movable carrying frames down to a certain limit and to reduce the use of the driving mechanism, it is advisable to divide the carrying frame into several connecting divisions and to position the cranks on adjacent divisions at 180° from each other, thus effecting a weight balance. In arranging the ends of the movable carrying frames care has to be taken that the sticks may be passed on from one movable carrying frame to the next one.

The revolving or turning of the spinning cakes is best done at the different places on each row, and at least once in each row for each division. At the place where the spinning cakes of a specific spinning stick must be turned, an additional arrangement is provided by means of which the spinning cakes are turned or turned over a certain amount. For instance, this may be done at the moment where the sticks with the spinning cakes are transported from one groove to the other.

In order to arrange the revolving or turning over of the spinning cakes in a better manner, the distance between the grooves where the spinning cakes of a washing stick are to be turned may be made a little greater than the others on the machine. This arrangement gives the necessary space not only for turning the cakes around, but also allows sufficient space for the revolving means and its movement. The greater distance between the grooves requires an additional transporting means at this place which is

actuated by means of the carrying frame to transport the washing stick, independently of the carrying frame, between these more widely separated grooves.

- 5 All the mechanisms for the driving of the movable carrying frames as well as for the side mechanisms may be coupled together and be driven from a single main drive shaft. The driving of the main drive shaft should be intermittent and arranged in such a way that the moving periods are relatively short and the resting periods and dripping periods relatively long.

Under spinning cakes, which should be used according to this process and with the above arrangement, we understand such cakes as are produced by means of the centrifugal viscose spinning process and which have already been previously twisted. However, in the same manner, more or less short or more or less crossed 15 skeins or other kinds of yarn bodies, particularly if they are wrapped in the above mentioned covers, may be used. In the same way this process and the machine may also be used for the dripping treatment of spooled yarn with or 20 without spools, provided that the yarn to be washed may be put together in some sort of transportable rows.

A showing of one arrangement is set forth in the accompanying sheets of drawings, in which: 30 Figure 1 is a cross-sectional view of the apparatus illustrating the cakes in position for treatment;

Figure 2 is a lengthwise cross-sectional view of the apparatus as shown in Figure 1; 35 Figures 3 through 6 show the transportation of the washing sticks from groove to groove on the fixed carrying ledges, Figure 5, including a fractional top plan view of the ends of the movable ledges.

40 Figures 7 through 10 show the arrangement for revolving or turning the cakes, and

Figures 11 and 12 are views of the intermittent driving arrangement of the machine.

As may be seen from Fig. 1, the spinning cakes 45 are hung on carrying sticks (1), i. e. glass sticks, rubber covered steel tubes, etc. These sticks rest with their ends on fixed rails (2), which have the necessary grooves for placing the sticks and are attached on both sides of the machine frame 50 in rows. Lengthwise of this arrangement and above the cakes, dripping boxes (25) are installed. This arrangement has been chosen so that the cakes hanging one under the other receive a regular drip washing through the respective drip boxes. After a certain time the stick is moved 55 forward lengthwise of the machine and thus passes through the entire arrangement. In this way the cakes pass one after the other all the different stages of the baths.

60 The transportation of the sticks containing the cakes (1) according to Figures 1 and 2, is effected on two fixed rails (2, 2) and two movable rails (3, 3), which rails have grooves on each side of the machine for placing the sticks. The movable rails are connected with cranks (4, 4) in such a way that each point of these rails (3, 3)—including also each groove—makes a full circle when the cranks (4, 4) are revolved. (See Figures 3 through 6.) If the grooves of the movable rails describe an upper half circle, the sticks (1, 1) lying in these grooves are moved from one set of grooves of the fixed rail (2, 2) to the next following set of grooves. While the lower half circle is described, the sticks (1, 1) remain 75 in the grooves of the fixed rails (2, 2). While

making the full circle the movable rails also stand still for a certain period of time. This procedure is always repeated and thus the sticks pass through the entire machine in regular intervals.

5 In order to make the machine more efficient and to obtain the most economical use of the bath liquids, the above mentioned arrangement of the rails according to Figures 1 and 2 is made in the form of rows on top of one another. The fixed rails (2, 2) are attached in a suitable manner to the fixed scaffold (5) whereas the movable rails (3, 3) are connected with a special frame scaffold (6) which is driven by the cranks (4, 4). This means a considerable simplifying of the 10 driving as otherwise each rail row would have to have a special driving mechanism.

The considerable length of the washing machine requires also a corresponding length of the frame scaffold (6). The cranks (4, 4) would 20 therefore have the very heavy onesided load of the driving mechanism and motor when lifting the heavy frame. In order to obtain the proper balance, the frame (6) has been divided into a number of equal parts and the cranks which drive 25 each single part are shifted by 180° in relation to those of the next following part. If one frame division goes upwards the next one goes downwards and a complete balancing of weight will result in the use of the cranks as far as the naked 30 frame weight is concerned.

For the transportation of the sticks carrying the cakes from one frame division to the next following, the rail ends facing each other are shifted sideways in the desired length according to Figures 3-6, so that these ends (7 and 8) may pass each other. The fixed rails, however, go uninterrupted through the entire fixed machine frame. This formation of the rail ends makes it possible for the last groove in the movable rail of the 40 first frame division to deposit the stick on the corresponding groove of the fixed rail and the first groove in the movable rail of the following frame division takes up the stick and passes it on.

It may be mentioned that the frame scaffolds 45 (6) may rest upon the cranks instead of hanging on the cranks, as shown on the attached illustrations.

In order to obtain a thorough washing it is preferable that the cakes be revolved at regular intervals. For this purpose the arrangement as shown on illustrations 7-10 for revolving the cakes 50 is built into the respective lengthwise divisions in the various rows.

On these illustrations (2) are the fixed rails 55 and (3) the movable rails. The machine parts connected to the movable rail (3), the pivot (9) and the small roller (10) describe the same circle as the pivot of the crank (4). The pivot (11) and the small bearing (12) are mounted on the 60 fixed rail. A fork (13) is fixed on the pivot (9), the lower part of which may be shifted on pivot (11). The lever (14) is fixed on the inside and lever (15) on the outside of the short axle of the bearing (12). At the end of the lever (14) is a revolving drum (16) and at the end of the lever (15) is the contacting surface for the small roll (10). The operation of this mechanism is as follows:

The fork (13) at the beginning of the movement, during which the pivot (9) makes the first portion of a revolution, catches the stick carrying the cakes in the groove (17) from below and deposits it at the end of its path in the groove (18), thereby laying the cakes carried on the stick 70 75.

on roll (16) at the same time. Until then the roll (16) remains in its lower position. As soon as the pivot (9) describes the lower circle or second portion of the revolution, the fork (13) returns empty and engages, at the end of its path, the stick which has, in the meanwhile, arrived in the groove (17). While the pivot (9) describes the lower circle, the small roller (10) makes the same movement and lifts the roll (16) into its highest position by pressing on the lever (15). In this way the cakes lying on roller (16) are turned around and fall back to the stick on groove (18) by which means the cakes have been completely revolved.

The peculiar dividing of the time between the motion and rest of the washing machine drive (from a full turn of crank (4) in about $\frac{1}{5}$ min. to a standstill of about 6-7 min.) requires a special arrangement for this drive. By the means of an electric time clock the electric motor may be stopped at the desired intervals. However, in this way it would be necessary to start the motor at full load and on the other hand it would be difficult to let the motor run for the specific time required to give the crank (4) exactly a full turn.

25. In order to eliminate both these difficulties, the following arrangement shown in Figures 11-12, is proposed:

On the shaft (19), which is also the crank drive shaft, a sprocket wheel (20) is wedged in, and on both sides of this sprocket wheel are two loose sprocket wheels (21) and (22) of the same size. Into these three sprocket wheels a triple endless chain (23) catches, the middle part of which has only as many bolts as the sprocket wheel (20) has teeth. The counter sprocket wheel (24) is fixed to the shaft (26) and has only two rings of teeth which engage the outer part of the triple chain. This enables the motor to start empty and at one turn of the chain the sprocket wheel (20) and also 40 crank (4) turn around just once. Between the above mentioned installation as per Figures 11 and 12, and the electric motor drive, is a suitable transmission gear. The motor itself is regulated by an electric time clock for the necessary intervals of motions and rest.

Having fully described our invention as required by the patent statutes, what we desire to claim is:

1. Apparatus for wet-treating artificial filament masses comprising a plurality of sticks for carrying the filament masses, spaced stationary members having spaced grooves for seating the sticks, means for advancing the sticks to other grooves and effecting turning of the filament masses about the sticks, and means for applying fluid to the filaments.

2. Apparatus for wet-treating artificial filament masses comprising a plurality of sticks for carrying the filament masses, mesh means to wrap the masses, spaced stationary members having spaced grooves for seating the sticks, means for advancing the sticks to other grooves and effecting turning of the filament masses about half a revolution around the sticks, and means for conveying fluid to the filaments.

3. Apparatus for wet-treating artificial filaments comprising a plurality of sticks for carrying the filaments, spaced stationary members having spaced grooves for seating the sticks, spaced members generally parallel to said stationary members, means for lifting the second-named spaced members and advancing the sticks to other grooves, and means for applying fluid to the filaments.

4. Apparatus for wet-treating artificial fila-

ments comprising a plurality of sticks for carrying the filaments, a plurality of pairs of spaced stationary members located above one another and having opposed spaced grooves for seating the sticks, means comprising a frame for intermittently lifting the sticks and advancing them to other grooves, and means for conveying fluid to the filaments.

5. Apparatus for wet-treating artificial filaments comprising a plurality of sticks for carrying the filaments, a plurality of pairs of spaced stationary members located above one another and having opposed spaced grooves for seating the sticks, means comprising a frame for intermittently lifting the sticks and advancing them to other grooves, and means for conveying fluid to the filaments, said last-named means comprising perforated trays above the top row of filaments for distributing treating liquid to the filaments and above each remaining row for receiving the drip therefrom and conveying it to the filaments next below.

6. Apparatus for wet-treating artificial filaments comprising a plurality of sticks for carrying the filaments, a plurality of aligned units each including spaced stationary members having spaced grooves for seating the sticks, movable members cooperating with each unit and adapted periodically to carry the sticks forward to other grooves and from one unit to another, and means for conveying fluid to the filaments.

7. An apparatus as defined in claim 6 in which the movable members of successively aligned units overlap.

8. An apparatus as defined in claim 6 in which a plurality of pairs of aligned movable members are actuated by the same means and are so positioned in relation to a driving means that one half of the units are being raised while the other half are being lowered.

9. Apparatus for wet-treating artificial filaments comprising a plurality of sticks for carrying the filaments, a plurality of aligned units each including spaced, generally parallel, stationary members having spaced grooves for seating the sticks, movable members cooperating with each unit and adapted periodically to carry the sticks forward to other grooves and from one unit to another, means including crank arms for shifting said movable members, and means for conveying fluid to the filaments.

10. An apparatus as defined in claim 9 in which the cranks of succeeding units are driven by the same means and are positioned at an angle of 180° from the cranks of the preceding units.

11. An apparatus for wet-treating artificial filaments comprising a stick for carrying the filaments, means to support the stick adjacent either end thereof, means to move the stick to another position, and means operative during moving of the stick for turning the filaments about the stick.

12. An apparatus for wet-treating artificial filaments comprising a stick for carrying a loop-shaped filament mass depending therefrom, means to advance the stick from one position to another, and means cooperating with the depending portion of the filament mass for lifting said depending portion in order to alter the position of the mass on the stick.

13. The combination as claimed in claim 12 wherein said last-named means comprises a roller adapted to engage the filament mass and lift the same while it is being moved.

14. The combination as claimed in claim 12

wherein said last-named means is adapted to swing the filament mass through about 180°.

15. An apparatus as described comprising a plurality of members for carrying filament masses, spaced stationary members adapted to support said carrying members, spaced movable members adapted to lift said carrying members and advance them to new positions upon said stationary members, and means cooperating therewith for subjecting said filament masses to liquid treatment.

16. An apparatus as described comprising a plurality of members for carrying filament masses, spaced stationary members adapted to support said carrying members, spaced movable members having their end portions supported by cranks extending in the same direction from rotatable parallel shafts, means for rotating said shafts a definite angle, and means cooperating with said carrying members for subjecting said filament masses to liquid treatment.

17. An apparatus as defined in claim 16 comprising means for reducing the starting loads upon the rotating means when the latter is operated intermittently.

18. An apparatus as defined in claim 16 in which the said shafts are rotated through 360° by means of a drive shaft having a pair of spaced chain sprockets fixed for rotation with it, a shaft adapted to rotate said cranks and having a pair of spaced sprockets rotatably mounted thereon,

spaced endless chains around said pairs of sprockets, a sprocket fixed to said crank rotating shaft between the rotatably mounted sprockets, and means connecting said spaced chains throughout a portion of their length for contacting with the teeth of said intermediate sprocket to rotate the same sufficiently to give the desired rotation to the said cranks.

19. An apparatus of the class described comprising a stick for carrying a loop-shaped filament mass depending therefrom, a pair of stationary members adapted to support said stick, a pair of longitudinally rotating members, and a pair of levers pivoted opposite each other on said longitudinally rotating members and guided by pins in said stationary members, said levers having seats in their outer end portions adapted to receive the stick and carry it from one position on the stationary bars to another.

20. An apparatus as defined in claim 19 comprising also a pair of levers pivoted opposite each other on the stationary members and actuated by pins on said movable members to lift the depending portion of the filament mass advanced by the levers pivoted upon the movable members.
